PRESSURE COOKER

James Harvey Chandler, Oak Park, Ill., assignor to
Ekeo Products Company, a corporation of Illinois

Application August 12, 1943, Serial No. 498,347

3 Claims. (Cl. 220—25)

1

This invention relates to pressure cookers of the type wherein an annular portion of the closure or cover extending beyond the area thereof corresponding to the area of the closure receiving opening is adapted to be confined within the container through upward pressure of said annular portion of the cover against an internal annular seat around the opening.

It is an object of this invention to provide a closure for use in conjunction with an internal seating arrangement of this character embodying features of construction whereby the introduction and removal of the closure are facilitated.

This invention accordingly contemplates the use of a closure adapted to be temporarily flexed into a shape wherein its dimension is sufficiently reduced to be passed through the cooker opening toward and away from a position below the annular seat within the cooker receptacle through the action of flexing mechanism directly associated with the closure.

These and various other objects and advantages are attained with this invention, as will be apparent from the following description, taken in connection with the accompanying drawings wherein the invention is shown in its preferred form, it being evident that other forms of construction and modifications may be adopted in carrying out the objects and purposes of this invention.

In the drawings:

Fig. 1 is a side elevational view with parts of the cooker receptacle in central vertical section, illustrating the arrangement of parts when the closure embodying the present invention is in operative relation to the receptacle.

Fig. 2 is a similar view, with parts omitted and a part of the receptacle broken away, illustrating the device shown in Fig. 1 when turned through an angle of 90 degrees.

Fig. 3 is a fragmentary top plan view of the same.

Fig. 4 is a side elevational view with parts of the cooker receptacle in central vertical section, wherein the closure is shown in flexed shape and prepared for insertion through the closure receiving opening of the receptacle.

Fig. 5 is an enlarged vertical section taken on line 5—5 of Fig. 4, with part of the receptacle included to indicate relative width of the closure and the closure receiving opening when the closure is flexed as shown.

Reference being had more particularly to the drawings, the numeral 10 designates a pressure vessel of a type with which a preferred embodiment

2

ment of a closure 15 of this invention may be effectively used. As illustrated, the vessel is of cylindrical shape having its side wall terminating at its upper limits in an inwardly and downwardly curled edge 11 to define a mouth or opening at the top of the vessel through which the contents of the vessel may be introduced or withdrawn. The curled edge 11 is adapted to receive a suitable gasket or packing member 12 in such a manner that the member 12 thus provides an annular downwardly facing seat within the vessel.

The closure 15 is circular in plan so as to provide an annular portion adapted to underlie the seat formed by the member 12 surrounding the closure portion corresponding to the area of the mouth of the vessel 10. The closure is made of relatively thin sheet metal or other suitable material which contains sufficient resiliency to permit of a certain amount of distortion (under the action of flexing means associated with the closure and more fully hereinafter described) whereby it may be temporarily sprung into a shape insertable through the mouth of the vessel as shown in Figs. 4 and 5, during movement toward and away from a position wherein the annular portion of the closure underlies the seating member 12.

Means for temporarily flexing the closure 15 are preferably provided through the use of a yoke or bar 13 adapted to extend across the closure 15, in the manner shown in Fig. 3, which yoke has a central aperture or bearing through which an axially projecting cylindrical stem or post 14, fastened as at 16 to the center of the closure 15, may project. The collar 17 fixed to the stem 14 provides a stop against which the yoke 13 may bear to prevent withdrawal of the stem 14 from the yoke. Movement of the stem 16 relative to the yoke 13 from a position wherein the collar 17 is engaged by the yoke 13 as shown in Fig. 5 to a position wherein the collar 17 is spaced upwardly therefrom accordingly causes the ends of the yoke to press against diametrically opposite surface portions of the closure 15 inwardly from the annular portion of the closure normally adapted to engage the seating member 12 whereby the closure is warped or flexed on an axis perpendicular to the longitudinal axis of the yoke 13. It will be observed that sliding movement between the opposite ends of the yoke 13 and the surface of the closure contiguous thereto incident to flexing of the cover is facilitated by giving a rounded or bulged shape 55 to said yoke ends. The yoke 13 is also provided

with a lateral extension or support 18 into which the shank 19 of a handle 20 may be fastened. The handle 20 is preferably of such length as to overhang the handle 21 secured to the side wall of a vessel 10 through a ferrule 22, when the closure 15 is in operative position as shown in the drawings.

Pivoted at 23 between the upper ends of a pair of spaced parallel arms 24 projecting upwardly from the outer end of the bracket or support 18 for swinging movement in a vertical path in alignment with the longitudinal axis of the closure handle 20, is a lever 25.

The inwardly projecting end of the lever 25 is forked as at 26 for the purpose of embracing a portion of the stem 14 between the collar 17 and a similar collar or projection 27 fixed to stem 14 and spaced upwardly from said collar 17. The closure 15 is accordingly forced into a diametrically warped shape against the opposite ends of the yoke 13 through pulling force exerted on the stem 14 upon upward swinging movement of the forked end of the lever 25. A thumb-piece 28 carried at the free outer end of the lever 25 provides a bearing which the user may press with the thumb of the hand which grasps the closure handle 20 whereby the lever 25 is easily operated to cause flexing of the closure. Upon release of pressure on the thumb-piece 28, the resiliency of the closure will immediately cause it to spread or relax into normal shape effective to position the annular edge portion thereof in a plane effective to engage the seating member 12. Because stem 14 provides a bearing or pivot on which the yoke 13 may turn, the axis on which the closure 15 is warped as described herein, may be varied as the relative angular position of the yoke 13 is changed with respect to a selected diametrical line across the closure. This arrangement makes it possible to avoid a permanent "set" or warped shape in the closure member 15 when it is no longer subjected to external flexing stresses by the yoke 13, which might otherwise develop where bending or flexing is confined to the same axis each time the closure is applied to or removed from the seat 12.

After the closure 15 is confined within the vessel and released from pressure of the flexing mechanism as above described, the closure 15 is adapted to be lifted into a position against the seating member 12 by rocking the closure handle 20 toward the vessel handle 21. A suitable fulcrum for this purpose consists of a downwardly projecting leg 29 provided at the inner end of the handle 20 which leg is adapted to pivot in a recess or seat 30 on the ferrule 22 of the vessel handle 21. The closure is preferably held in place against the seating member 12 by any suitable means such, for example, as a latch 31 mounted for swinging movement on the handle 20 toward and away from a position in engagement with the vessel handle 21 as shown in Figs. 1 and 4. As the closure 15 is moved upwardly toward the seating member 12 through rocking movement of the closure handle 20 on its pivot as aforesaid, a pair of ridges 32 and 33 at transversely opposite internal sides of the vessel 10 and arranged vertically below the seat 12 are adapted to be engaged by the edges of the closure 15 whereby the closure may be easily guided into a central position with reference to the mouth of the vessel.

As pressure is built up within the vessel 10 it is apparent that the closure 15 will be more tightly pressed against the seat member 12 so

as to provide a more effective leak-proof seal between the seat member 12 and the surface of the closure 15. In order to provide a vent through which steam pressure may be released as desired, the stem 14 is preferably hollow throughout its length thereby forming a passage in communication with the interior of vessel 10. Under this arrangement the upper end of the stem 14 provides a seat for a suitable valve such as a weight 34 as shown in Fig. 5. A safety steam vent in the form of a rubber plug 35 may also be fitted on the closure 15. The particular type of fittings described and shown herein are, however, merely indicative of any suitable form of fitting adapted for use in connection with a pressure cooker as contemplated by this invention.

A thin flexible closure member, such for example as a circular disc of sheet metal stock of .018 inch to .020 inch thickness, of suitable spring temper, with only the use of a relatively flat smooth peripheral face portion in contact with the underside of a rigid circular annulus surrounding the opening in the top of a container, such for example as a two-quart capacity drawn cylindric vessel of sheet metal stock of .040 inch thickness, corresponding substantially to the shape of vessel 10 as shown in the drawings, including an inwardly curled edge 11, is illustrative of one preferred embodiment of a pressure container as contemplated by the present invention. However, it will be apparent that various changes might be made in the structure and design of the elements involved in said example to form a pressure container of the general character described, all without departing from the spirit of this invention as defined in the annexed claims.

What is claimed is:

1. In a pressure cooker, a vessel having an opening through which contents of the vessel may be admitted or discharged, a downwardly facing seat within the vessel surrounding said opening, means engageable with said seat to seal said opening including a flexible closure member having an annular portion extending peripherally beyond the area thereof corresponding to the area of said opening and adapted to be temporarily flexed into a shape enabling its passage through said opening toward and away from a position wherein said closure engages said seat, a rigid yoke member having contact faces presentable toward upper surface portions of the closure in downwardly advanced position relative to the central portion of the yoke against which diametrically opposite upper surface portions of the closure located inwardly from its annular portion may be drawn upwardly to flex the closure into a shape enabling its passage through said vessel opening when the central portions of said yoke and closure are in vertical alignment, means for maintaining said central portion of the yoke and said central portion of the closure in vertical alignment including a stem fixed to and projecting upwardly from the central portion of the closure, said yoke and stem being connected for relative movement axially of said stem between an advanced position wherein said closure is placed under strain by said contact faces of the yoke to flex the closure into a shape enabling its passage through the vessel opening and an initial position wherein said closure is freed from strain to resume its normal unflexed shape, a handle having a forward portion fixed to said yoke and a rearward portion which projects laterally beyond the edge of the closure and about which a

hand may be flexed into operative position to support the closure, a lever movable about an axis in fixed relation to said yoke and operatively engaging said stem for moving said stem from initial position to advanced position relative to said yoke, said lever having a free end operable in such proximity to the handle throughout the travel of the lever between initial and advanced positions of the stem relative to said yoke as to be within range of normal movement of the thumb of the hand operatively flexed about said handle whereby the lever may be operated to move said stem from initial position to advanced

- 10 5 position relative to said yoke through the agency of pressure applied on said free end of the lever by said thumb.
2. In a pressure cooker as defined in claim 1, means providing a steam vent in communication with the interior of said vessel when said closure is in engagement with said seat including a passage extending lengthwise through said stem.

3. In a pressure cooker as defined in claim 1 wherein said yoke and stem are connected for relative pivotal movement about said stem as an axis.

JAMES HARVEY CHANDLER.
